William S. Blum
Attorney.

UNITED STATES PATENT OFFICE

ABRAHAM LEVINE, OF ELIZABETH, NEW JERSEY, ASSIGNOR TO PRESTO LOCK CORPORATION, OF NEW YORK, N. Y., A CORPORATION OF NEW YORK.

COMBINATION LOCK

Application filed October 19, 1929. Serial No. 400,836.

My present invention relates generally to combination locks and more particularly to locks intended for use with a trunk, valise, or the like.

Combination locks of the types now generally employed are dependent upon visual indications for guidance in their operation and as an example I make reference to the combination lock described in my co-pending application, Serial No. 364,726, filed on May 21, 1929.

One of the difficulties attendant upon the operation of a lock which depends for its guidance and operation upon visual indications, is that when employed, as for example, on a trunk on the rear end of an automobile, it will be necessary to employ a source of illumination to permit of its operation, and which may be made available only with difficulty, if at all.

One of the objects of my invention is the provision of an arrangement in the combination lock of means whereby its operation can be guided or made dependent upon sound or feel or both and in the embodiment of the invention herein disclosed the operation is dependent upon a step by step movement given to the dial which movement is distinctly apparent to the touch and which is also ascertained by a clicking noise each time the dial is moved an increment, along with an arrangement whereby the same predetermined starting point can always be arrived at even while in the dark.

For the attainment of the foregoing objects and such other objects as may hereinafter appear or be pointed out, I have illustrated one embodiment of my invention in the accompanying drawings wherein—

Figure 1 is an elevational view partly broken away;

Figure 2 is a cross-section taken on line 2—2 of Figure 1;

Figure 3 is a front view of the face plate; and

Figure 4 is a perspective of the dial and its spindle.

In Figure 1 of the drawing I have shown in dotted lines part of trunk elements 10 and 11 (i. e. the bottom and top). These are kept

closed by the engagement of a hasp 12 carried by the body of the trunk over a hook 13, carried by the cover in the well known manner. The hasp or hook 12, is dependent for its operation upon manual manipulation of the hand-grip 15 which in turn is dial controlled. 20 is a face plate carried by the trunk body and within which the lock mechanism is received. This face plate is provided with the generally circular opening 21 through which is received the spindle portion 22 of the dial member 23. The tumblers (not shown) forming part of the lock mechanism to be received within the face plate 20 are controlled in their operation by the rotation of the dial in any preferred or desired manner and in my co-pending application, Serial #364,726 and above referred to, I have described in detail a lock construction which could be employed in connection with the dial member 23 of the present application and no detailed disclosure of such lock construction is made herein because it is deemed unnecessary to an understanding of my invention.

The opening 21 while generally circular in outline is provided with a plurality of notches or depressions, six being shown in the illustrated embodiment. All but one of these notches are illustrated as alike and further reference will be made to the character of these depressions or notches and the reasons for the dissimilarity of one of them.

Upon comparing Figures 1 and 4 it will be observed that the dial is provided with the reduced neck 30 which in turn is connected with the spindle portion 22, which is of a still further reduced diameter. A groove or channel 33 is cut diametrically into the dial shank on a level with and below the lower surface of the dial 23. This will have the groove formed through the neck 30 and the adjacent portion of the spindle 22. The groove is preferably made of a depth sufficient for the purpose desired and is illustrated in the drawings as extending more than half way through the spindle. An expansion spring 35 is received within the groove to act against the ball 36 of a size to be received within the groove or channel.

The opening 21 in the face plate 20 is of a

diameter so as to receive the spindle 22 therethrough for guided rotation therein. Those notches in the face plate which are alike, as already referred to, and to which the reference character 26 has been applied are of a character so that as the dial is rotated, the ball 36, which is continuously spring-pressed into engagement with the wall of the opening 21, will fall into these notches 26 and 5 tend to resist further rotation of the spindle and to prevent a continued rotation of the spindle except by the application of an increased pressure and on the other hand in falling into these notches 26 the balls will 10 produce a clicking noise. The balls and the notches are arranged contoured and dimensioned so as to have this desired and intended effect.

The notches 26, it will be observed, are 20 symmetrical radially of the opening 21. As a result of this, the cooperation of the ball 36 and the notches 26 will be the same whether the dial is moved clockwise or counter-clockwise.

25 The notch 27, on the other hand, has its adjacent contour portions 27' and 27'' which make up the notch 27, unsymmetrically formed. The portion 27' in the illustrated example is so contoured and dimensioned 30 that when the ball 36 is received in the notch 27 any clockwise movement of the dial will be prevented and the dial will be locked against further clockwise movement when this position is reached. The wall portion 25 27', on the other hand, is so sloped and contoured that with the dial positioned as set forth, no substantial resistance will be offered to the counter-clockwise movement of the dial and the ball will be able to freely ride over 40 this contour.

From the description above given the operation of my device will be understood. Let us assume that the combination is three to the left, that is counter-clockwise, and two 45 to the right, that is clockwise, and that the combination is to be operated in the dark. A person moves the dial clockwise until it is locked against further movement, which will happen when the ball 36 moves into the 50 notch 27. He then starts moving the dial counter-clockwise and as the ball moves into the first notch 26 to the left of 27 a clicking will be heard and in addition this happening will be obvious because of the slightly increased resistance. A further increment of 55 movement is given to the dial upon which a further clicking will be heard and then a third movement in the same direction with a third clicking. The clockwise movement is 60 then begun, the successive increments of movement being indicated to the finger by the change in the resistance and to the ear by the clicking noise. The combination will thus have been effected and the trunk lock 65 freed for manual operation.

Having thus described my invention and illustrated its use, what I claim as new and desire to secure by Letters Patent is—

In a combination lock, a dial plate having an opening therethrough, and having a series of spaced notches in the wall defining said opening, a lock controlling member mounted for rotation relatively to said plate and having a portion received within said opening and which portion serves as a bearing for said controlling member in its rotation, a spring-pressed member carried in said bearing portion and movable radially into engagement with said notches in succession as the lock controlling member is rotated 70 to limit such rotation to successive increments of movement, said spring pressed member being confined within said bearing portion and wholly inaccessible from the exterior of the lock, and one of said notches having means for preventing movement of the lock controlling member in one direction.

In witness whereof I have hereunto signed my name.

ABRAHAM LEVINE.
